UNITED STATES PATENT OFFICE

GEORGE KELLY, OF MINERAL POINT, WISCONSIN.

PRESS.

958,813.

Specification of Letters Patent.

Patented May 24, 1910.

Application filed July 25, 1907. Serial No. 385,576.

To all whom it may concern:

Be it known that I, GEORGE KELLY, a citizen of the United States, residing at Mineral Point, in the county of Iowa and State of Wisconsin, have invented a new and useful Press, of which the following is a specification.

In the manufacture of thin strips, sheets and plates, for instance, vulcanized insulating boards, slabs, and the like, it has heretofore been difficult to press, heat and dry a large number of the same in one press, because of the bulk of the division plates. Moreover these structures are exceedingly expensive.

It is the primary object of the present invention to provide means which will effectively press, heat and dry insulating slabs, boards, sheets or other material, said means permitting the employment of a comparatively great number of combined heating and division plates, which are thin, and will consequently allow a large number of slabs or sheets to be simultaneously acted upon.

Heretofore in the process of vulcanizing thin sheets of material as above referred to, it has been found necessary to use steam-heated platens, that is, a series of hollow boxes into which steam is conducted, these boxes being interposed between the sheets of material. These steam-heated platens are expensive, they are relatively difficult to connect up with steam supply pipes, they must be made heavy to withstand the steam pressure and the compressing force, and they have to be made of considerable thickness—each hollow platen in practice being about four inches thick. As above stated, such presses are expensive, in a ratio depending upon the number of platens they use. Where presses have only two platens, formed by the follower and the bed plate, the presses are in no way adapted for vulcanizing thin sheets of material in large quantities, for the reason that only one sheet at a time can be properly pressed and vulcanized. If more sheets are placed between the platens, the outer ones are properly dried, but the inner ones are either not dried sufficiently at their middles, or then the margins of the sheets are burned before the interior of the sheets is properly dried. It will be obvious that even with larger presses having interposed steam-heated platens, it will be impossible to press and vulcanize any quantity of thin sheets at a time and prop-

erly heat them, for the reason that the sheets must be separated by platens four inches in thickness. Hence, only a few sheets at the best can be dried in these presses, because for every two sheets 12 inches of press space must be taken up by three platens. Of course, a plurality of sheets may be placed between separated platens, but when this is done the same difficulty occurs as above stated, namely, that the sheets are unequally heated and dried, and that, if the middle sheets are properly heated, the outer sheets are very liable to be burned or heated too much. There cannot be, under these circumstances, any uniform heating of the sheets. These thin flat sheets of vulcanized board or insulator material are particularly troublesome to dry because of their tendency to warp, and heretofore—because of the fact that presses could not be used practically for this purpose—it has been customary to dry the sheets by spreading them out and weighting them down, a step naturally requiring a very large floor space and a great deal of work, with hardly the best results.

I overcome these difficulties and render possible the use of a press for drying a multiplicity of thin flat sheets by using, with an ordinary press, a series of thin flat electrically-heated plates. A sheet of material is first placed in the press and then a sheet of thin metal, then a sheet of material and then another sheet of metal, and so on until the press is filled. As these metal sheets or plates are very thin, they practically take up very little room, and, as a consequence, the press may be filled with a large number of sheets of material to be vulcanized. Each of these interposed plates of metal is connected to a suitable source of electric current to heat the same, and it will be obvious that each of the plates will be heated evenly over its entire surface and that this heat may be regulated to just the required amount. It will be plain, therefore, that every sheet of vulcanizing material in the press will be uniformly heated without regard to its position in the press, that the heat will be distributed over the entire surface of the sheet, that in consequence of the uniformity of the heat, all sheets will be dried in the same length of time without danger of some sheets being burned and some under-dried, and, that, therefore, the entire process will be very much expedited. It will also be seen that the sheets are dried and held under

compression at the same time so that they cannot warp, and that far less floor space is required than with the process now followed. It will also be plain that my invention may 5 be used with an ordinary cheap press, that the electrical connections may be very simple, and that the use of heavy platens, difficult to handle and difficult to heat, to say nothing of their cumbersome thickness, 10 is entirely done away with. It will be plain that the heating plates may be changed in position or number to suit any particular requirement, and that my device is as applicable to one form of press as another. 15 The preferred embodiment of the invention is illustrated in the accompanying drawing, which is a side elevation of a press, constructed in accordance with the present invention, and showing the electric current 20 supplying means diagrammatically.

In the embodiment illustrated, a press is employed comprising a frame 1, in which are mounted relatively movable pressing members 2 and 3. These members may be 25 of any suitable structure or type well known to the art, and in the present embodiment, the movable member is uppermost and is operated by hydraulic devices 4.

Located between the pressing members 30 are a plurality of comparatively thin division plates 5 which constitute electrical heaters, and are therefore preferably made of suitable resistance material. Through these plates a current of electricity is passed, 35 and the slabs, sheets or other material, shown at 6, are placed between them.

While the electric current may be supplied to the plates in different ways, in the preferred form of construction, spaced conductor bars 7 and 8 are located at each end of 40 the press longitudinally of the path of movement of the plates, and leads 9 and 10, connected respectively to the conductors 7 and 8, extend from a suitable generator 11. 45 In the leads 9 and 10 are located an ammeter 12, a voltmeter 13, a suitable switch 14, and fuses 15. The generator, which is preferably of the alternating type, is provided 50 with a suitable rheostat 16, and an extinguisher 17.

The current may be supplied from the conductors 7 and 8 to the heating or resisting plates 5 in a plurality of ways. Thus in the embodiment disclosed, collars 18 are 55 slidably mounted on the conductors, and have suitable sockets 19, in which connecting devices 20 may be engaged, said devices being also connected in sockets 21 formed in the ends of the plates. In the structure disclosed, 60 the plates are located in series, and therefore one of the conducting devices 20 is connected to one of the collars 18 on one of the conductors 7, the other end being connected to the uppermost plate. The 65 lowermost plate in like manner, is connect-

ed at its opposite end with the opposite conductor 8. The adjacent plates are furthermore connected by flexible conductors 22. It will thus be evident that when the circuit is closed, the current will pass through all 70 the plates, and heating the same, will heat and dry the material placed between them. At the same time, the material will be pressed and held in flattened condition until thoroughly dry, and in case material that 75 can be vulcanized is placed between the plates, said material will be vulcanized.

One of the particular advantages secured in the present structure is the equal heating, 80 drying and vulcanizing action secured, for with thin sheets the central portions are properly dried and vulcanized completely through without the outer portions or faces being burned. Another important advantage follows from the use of relatively thin 85 combined heating and division plates, in that the capacity of the press in which the plates are substituted for steam heated platens, is materially increased. For instance, in a hydraulic press having a sufficient number 90 of steam heated platens for compressing about four sheets of rubber matting or the like, it is possible, by the use of plates, to compress as many as fifty sheets of vulcanized insulating boards, and in some 95 presses the output in the number of sheets can be increased twenty or more times.

Instead of arranging the plates in series, as disclosed, they may be connected in multiple in which case, it is evident that each 100 plate is separately connected to one of the conductors 7, and the opposite conductor 8, the additional collars 18 being employed for this purpose. Thus it will be evident that the electric current can be supplied to the 105 plates in a variety of ways, and simple means is thus provided, whereby a large number of sheets, slabs, boards and the like can be thoroughly heated, dried, and at the same time held in flattened condition. 110

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention. 115

Having thus fully described my invention, what I claim as new, and desire to secure by Letters Patent, is:—

1. In a press of the class described, the combination of upper and lower relatively- 125 movable platens, a plurality of combined heating and division plates disposed between the platens each consisting of a solid sheet having smooth upper and lower faces and constructed of material which rises in tem- 130

perature on the passage of an electric current therethrough, said sheets being arranged alternately with the material to be compressed and dried, and means for connecting the sheets in circuit with a source of electro-motive force whereby opposite sides of the plates in contact with the material are substantially uniformly heated.

2. The combination with a drying press having upper and lower platens, of a plurality of movable division plates adapted to be located between and in the midst of the material being pressed, said plates being flat and smooth on opposite sides and composed of thin imperforate solid homogeneous sheets of electrically-resisting material with means whereby a current of electricity may be passed into each of them.

3. In a drying press, opposed platens, a series of thin solid homogeneous metal plates of electrically-resisting material adapted to be interposed alternately between the sheets of material to be dried, and means for separately and uniformly heating said plates by connecting them to a source of electrical energy.

4. In a press for drying and pressing sheets of material, the combination with pressing platens, of a plurality of thin flat solid imperforate drying plates of material having electrical resistance, adapted to be interposed between layers composed of material being dried and in contact therewith, and movable conducting means connected to the several plates for heating the same.

5. In a press for drying and pressing sheets of material, the combination with pressing platens, of a plurality of flat solid imperforate drying and pressing plates of material having electrical resistance adapted to be interposed between layers of said ma-

terial and in contact therewith, an electrical conductor located longitudinally of the path of movement of the plates, and a conducting device connected to each plate and freely movable with the same, said device having a freely movable engagement with the conductor.

6. In a press for drying and pressing sheets of material, the combination with pressing platens, of a plurality of flat solid imperforate drying and pressing plates of material having electrical resistance, said plates adapted to be interposed between the layers of the material being dried, electrical conductors disposed longitudinally of the path of movement of the plates, connections between the conductors and certain plates adapted to permit a free movement of the plates, and electrical connections directly between the plates.

7. In a press for drying and pressing sheets of material, the combination with pressing platens, of a plurality of flat solid imperforate drying and pressing plates of material having electrical resistance, adapted to be interposed between layers of the material being heated, conducting rods arranged at the ends of the plates and connected to a source of electricity, devices freely slideable on the conductors and connected to the plates, connections between the conductors and certain of the plates to effect the movement of said devices with the plates, and flexible electrical connections between the plates.

In testimony that I claim the foregoing as my own, I have hereto affixed my signature in the presence of two witnesses.

GEORGE KELLY.
